WEAVING APPARATUS

Ralph Fisher, New York, N. Y., assignor of one-half to Oregon Worsted Company, Portland, Oreg., a corporation of Oregon

Application September 28, 1935, Serial No. 42,562

2 Claims. (Cl. 139—34)

The invention relates to improvements in weaving apparatus and has for its object the provision of a simple apparatus of the character indicated upon which simple weaving operations may be performed and which is of simple construction and capable of economical production.

Other objects will appear hereinafter.

The invention consists in the combinations and arrangements of parts hereinafter described and 10 claimed.

The invention will be best understood by reference to the accompanying drawings forming a part of this specification and in which

Fig. 1 is a top plan view of weaving apparatus 15 embodying the invention and shown in position of use;

Fig. 2, a side view of the same;

Fig. 3, an enlarged partial view of one end of the apparatus illustrating the method of weaving;

20 Fig. 4, a view illustrating the method of employing the apparatus for continuing the weaving beyond the normal length of the apparatus;

Fig. 5, an enlarged transverse section of a portion of the weaving produced on the apparatus;

25 Fig. 6, a partial end view illustrating the manner of weaving in the ends of the warp strands to prevent ravelling and to finish properly the end of a woven strip;

Fig. 7, a view similar to Fig. 1 but showing a 30 modified form of construction;

Fig. 8, a side view corresponding with Fig. 7;

Fig. 9, another view similar to Fig. 1 but showing still another modification; and

Fig. 10, a side view corresponding with Fig. 9.

35 The embodiment of the invention illustrated in the drawings comprises a rectangular weaving frame having a clamping member at one end consisting preferably of two wooden cross bars 10 adjustably secured together by means of clamping bolts 11 and wing nuts 12. Projecting from one of the clamping bars 10 are two parallel side members 13, preferably formed of metal rods having their ends adjustably secured in sockets 14 in said clamping bar.

40 A stretching bar 15, preferably of wood, is secured to the other ends of the side bars 13 by means of sockets 16 corresponding with the sockets 14, as will be readily understood.

45 In performing the weaving operation a plurality of warp strands 17 are doubled at 18 around the bar 15, arranged and stretched in substantially parallel relation between the clamping bars 10 with the ends 19 of said strands projecting from the clamp 10 any lengths desired for the length 50 of the woven strip to be formed.

A shuttle needle 20 is provided at one end with an eye 21 and at its other end with a rounded point as shown, the weft strand 22 of the weaving being threaded through the eye 21 as indicated in Fig. 3. The shuttle needle is then utilized, as indicated, to pass the weft strand 22 alternately over and under the warp strands 17, the same being doubled around the side bars 13 and then returned through the weft strands in opposite over and under relation until the entire space 10 between the clamp 10 and the bar 15 has thus been filled with weft strands. When this has been done the clamp 10 is released sufficiently to permit of the drawing of the strands 17 therethrough and the bar 15 is then withdrawn from the ends 15 of the rods 13 and the entire weaving pulled ahead until another suitable length of the stands 17 is thus drawn through the clamp 10, whereupon the bar 15 is properly threaded over and under through the strands 17 and replaced on the 20 ends of the rods 13, as indicated in Fig. 4. Then the ends of the strands 17 and 22 are drawn or tightened until the weaving is properly consolidated to remove undesirable looseness in the weaving. Thereupon the clamp 10 is again tightened 25 and the weaving continued as indicated at the bottom of Fig. 4 until substantially the full lengths of the strands 17 have been utilized in the weaving. The weaving should be stopped at a point where sufficient unwoven lengths of the 30 ends 19 of the strands 17 remain to permit of tying of said ends to form a fringe or weaving said ends back into the strip, as indicated in Fig. 6, to prevent ravelling and provide a proper terminal for the weaving.

If desired, a suitable comb or guide member having teeth projecting between the strands 17 may be secured to the clamp 10 to facilitate the movements and proper arrangement of said strands in the weaving frame.

If desired, a heddle or harness in the form of a looped thread may be passed as indicated under one set of the warp strands 17 so as to permit of simultaneous raising of said strands to form a shed to facilitate the passage of the shuttle needle 45 20 in one direction, thus materially facilitating the weaving operation. Obviously the woven strips thus formed may be utilized for various purposes and formed of strands of various materials and colors. The specific form and arrangement of parts constitutes a simple and effective one for the purpose.

In the modification illustrated in Figs. 7 and 8 another clamp 10 is substituted for the stretching bar 15 and the side bars 13' are made flat in- 55

stead of cylindrical. In the use of this arrangement the strands 17 are not looped or doubled but are stretched singly between the clamps 10, the weaving however being conducted precisely 5 as before.

In the modification illustrated in Figs. 9 and 10, a weaving frame is made up as indicated of two substantially L shaped flat bars 23 and 24 having their shorter limbs 25 and 26 overlapped and 10 cured together by clamping bolts 27, thereby forming a clamp for clamping one end of the strands 17. The other end of the frame is formed by transverse stretching bar 28 secured to the bars 23 and 24 by means of clamping bolts 29.

15 In this arrangement single strands 17 are held at one end between the clamping bars 25 and 26 and at their other ends are tied by simple knots 30 to the stretching bar 28. The weaving operation is conducted exactly as before.

20 While I have illustrated and described the preferred form of construction for carrying my invention into effect, this is capable of variation and modification without departing from the spirit of the invention. I, therefore, do not wish 25 to be limited to the precise details disclosed, but desire to avail myself of such variations and modifications as fall within the scope of the appended claims.

I claim:

1. A construction of the class described comprising a clamping member having two clamping bars adjustably secured together, one of said bars being provided with a plurality of sockets 5 to receive removably the ends of frame bars; a stretching bar having sockets corresponding with those in said clamping bar and adapted and arranged to receive the other ends of said frame bars; and strands doubled around said holding bar having their ends passing between said clamping bars in substantially parallel relation.

2. A construction of the class described comprising a clamping member having two clamping bars adjustably secured together, one of said 15 bars being provided with a plurality of sockets to receive removably the ends of side frame bars; side frame bars around which the weft thread may be woven; a stretching bar having sockets corresponding with those in the first said clamp- 20 ing bar and adapted and arranged to receive the other ends of said side frame bars; and strands doubled around said holding bar and having their ends passing between said clamping bars in substantially parallel relation. 25

RALPH FISHER.
